UNITED STATES PATENT OFFICE

CHARLES F. LARSEN, OF NEW YORK, N. Y.

IGNITER

Application filed December 27, 1926. Serial No. 157,186.

This invention relates to igniters of the pocket type in which a spark is formed by a suitable agency to ignite a wick saturated with alcohol, gasoline, or the like.

5 It is the special object of the invention to devise a construction which can be manufactured at a low cost, can be operated with one hand, and one which will function dependably. Another object is to provide the igniter with means which keep its closing cap tightly shut when not in use to prevent leakage of the liquid used as a fuel, the same means causing a quick working of the opening mechanism whereby the forming of the 10 spark is made certain.

With these and other objects in view, my invention consists in the novel combination of parts of which a preferred embodiment is described in the following specification and 20 illustrated in the accompanying drawings in which.

Fig. 1 is a longitudinal sectional view of the igniter in a closed or normal position;

Fig. 2 is an exterior view of the igniter in 25 an open or working position, showing part of the spark forming device in section;

Fig. 3 is a vertical cross sectional view along the plane of line 3—3 in Fig. 1;

Fig. 4 is a plan view of the igniter; and 30 Fig. 5 is a horizontal sectional view along the plane of line 5—5 in Fig. 1.

Like numbers of reference denote similar parts throughout the several views and the following specification.

35 10 is the container portion of the device comprising a tube having its top end flared outwardly at 11, and its bottom end threaded interiorly to receive a knurled cap 12. 13 is a cup-shaped cap pressed into the top end of the tube 10, its sides 14 fitting snugly the inner diameter of the tube, its closed top 15 being substantially flush with the top end of the tube and having an opening 16 there- 40 through. 17 is a wick within the inner part of the cup 13 having one end projecting outwardly thereof through opening 16. 18 is a wad of absorbent material, such as cotton, which fills the inner part of the tube 10 and 45 contacts with wick 17. This material is sat-

urated with a suitable liquid such as benzine, gasoline, alcohol, or the like.

19 is another tube, smaller in diameter and substantially parallel to tube 10 and fastened thereto by a rib 19^a, open at its top and closed at its bottom but for a small central opening to receive a plunger rod 20 outwardly projecting thereof and terminating in a handle knob 21 suitably fastened thereto, the other end of the plunger rod being enlarged 55 in diameter at 22 to form a plunger slidably fitted within the inner face of the tube 19. 23 is a coil spring around the plunger rod 20 bearing against the underside of the plunger 60 22 and the closed bottom of the tube 19, exerting an upward pressure against the plunger. The top of the tube is slotted at 24 to receive a wheel or scraper 25 revolvably mounted within the slot upon a pin 26. About one-quarter of the face of the wheel 25 is serrated as at 27. 28 is a pin of spark forming material, such as flint, soft metal, or the like, 65 slidably mounted within the tube 19 between the wheel 25 and plunger 22, which latter, because of spring 23, forces this pin against the face of the wheel 25. 28^a is an opening at the 70 side of tube 19 to permit the pin 28 to be inserted into this tube.

29 is a cap over the top of container 10 of substantially cup-shaped form having its 80 open end seat on the flared out top 11 of the container around the top of cap 13. 30 is a U-shaped extension of the cap 29 adjacent its top and fitted or, preferably, soldered to the upper face and sides of the wheel 25. 31 is a fingerpiece projecting laterally from the extension 30. Adjacent its open bottom, the cap 29 has a protuberance 32 forming a cam substantially triangular in cross section, its apex being adjacent the open bottom end of the cap, and having a base 33 form a stop for a ball-shaped terminal 34 of a spring 35 fastened securely to the side of the container 10. 85

In operating my device, the fingerpiece 31 is depressed. This movement lifts the cap 29 and causes the wheel 25 to revolve about 26, and brings the cap into the position shown in Fig. 2. In the normal or closed position, shown in Fig. 1, the spark forming pin 28 is held in close contact with the blank face of the 90 100

wheel 25, but while being opened, the serrated face 27 of the wheel is passed over the end of pin 28 which causes sparks to be thrown toward the wick and ignites the same. The ball-shaped terminal 34 of the spring 35 normally keeps the cap 29 tightly closed, preventing leakage of the fuel used through the top of the container. While, however, the fingerpiece 31 is being depressed, because 10 of the pressure of the spring 35, it is necessary to exert a little pressure in doing so, which causes the cap to swing open quickly. By this quick action the serrated face 27 of the wheel 25 is passed over the flint 28 very 15 rapidly, resulting in the certain sparking of the device.

The igniter described is obviously of a very simple construction and has relatively few moving parts. The wheel 25 which in the 20 customary constructions heretofore in use, was a ratchet wheel operated by a pawl and serrated on its entire face, is now a plain circular disc, serrated at only a portion of its face, resulting in marked economy of manufacture.

While I have shown the cap 29 with extension 30 and fingerpiece 31 fastened to the wheel 25, it is of course obvious that these parts can be made as one integral unit in 30 which case the part 25 cannot properly be called a wheel, but rather a case.

I wish it to be understood that various other modifications in form, proportion and combination of parts may be resorted to without 25 departing from the principles of the invention, as defined in the appended claims.

What I claim as new, is:

1. In an igniter having a container for fuel-saturated cotton and a wick projecting 40 therefrom, a sparking device comprising a wheel, having a partly serrated face, a sparking member normally in contact with the non-serrated face of the wheel, a fingerpiece projecting from and integrally connected to the said wheel to revolve the wheel and bring the said serrated face in rubbing contact with the said sparking member, a cap fastened to the said wheel, adapted to fit over the wick end of the said container when the igniter 45 is in a closed position and adapted to revolve with the said wheel to an open position when the serrated face of the wheel is brought in contact with the said sparking member, the said cap having a cam-like protuberance, and 50 a spring secured to the container having a terminal engage the said protuberance when the cap is normally in a closed position.

2. In an igniter having a container for fuel-saturated cotton and a wick projecting 55 therefrom, a tube alongside of the container holding a spark forming device, comprising a wheel revolvably mounted within a slot in the tube, having a portion of its face serrated, a sparking member normally held in 60 contact with the non-serrated face of the said

wheel, a cap, tightly fitted over the wick end of the said container and rigidly secured to the said wheel, having a fingerpiece projecting therefrom adapted to revolve the said wheel to bring its serrated face in rubbing contact with the said sparking member while the cap is being revolved to an open position, the said cap having a cam-like protuberance, and a spring, secured to the container, having a terminal engage the said protuberance when the cap is normally in a closed position.

In testimony whereof I have hereunto set my hand.

CHARLES F. LARSEN.
